UNITED STATES PATENT OFFICE.

LONARD KUCKARTZ, OF PORTLAND, OREGON.

WAREHOUSE GANG-PLANK.

SPECIFICATION forming part of Letters Patent No. 502,568, dated August 1, 1893.

Application filed April 17, 1893. Serial No. 470,663. (No model.)

To all whom it may concern:

Be it known that I, LONARD KUCKARTZ, of Portland, in the county of Multnomah and State of Oregon, have invented a new and useful Improvement in Warehouse Gang-Planks, of which the following is a full, clear, and exact description.

This invention relates to improvements in gang planks that are provided to afford a removable gangway from a warehouse to a car, or the reverse; and has for its objects to provide a novel, simple and practical device of the character indicated, which will be adapted for easy stowage below the floor of the warehouse, be convenient for an extension therefrom and adjustment for service, and also be adjustable in its parts, to suit cars the floors of which vary in height with regard to the floor of the warehouse having the improvement.

To these ends my invention consists in the construction and combination of parts, as is hereinafter described and claimed.

Reference is to be had to the accompanying drawings, forming a part of this specification, in which similar letters of reference indicate corresponding parts in all the figures.

Figure 1 is a side view in section, of the improvement extended from a warehouse to a car. Fig. 2 is a transverse sectional view of the device and a warehouse floor in part, on the line 2—2 in Fig. 1. Fig. 3 is an enlarged side view of an end portion of the improvement, removably engaged with a car in part. Fig. 4 is a side view of the gang plank end portion represented in Fig. 3, differently engaged with a car portion, shown by dotted lines. Fig. 5 is an enlarged plan view of a portion of the improved gang plank; and Fig. 6 is a side view of a warehouse in part, and a portion of the improvement in place thereon.

The improved gang plank A comprises a strong rectangular frame structure of a suitable length and width, its dimensions being proportioned to conform with the requirements of the location and service to be afforded by it. Preferably the gang plank A is constructed with two wooden strips a of equal size, their length representing that of the structure they are members of. A series of transverse tread boards b is secured upon the strips a by their ends, and may be spaced

apart slightly to permit dirt to fall between them and also to lighten the gang plank, a sufficient number of the pieces b being provided to afford a flooring for the gang frame or "plank," as the device is technically termed.

It is part of the improvement to provide means for the quick and easy stowage of the gang plank A below the floor B' of a warehouse B, which floor is to be sustained horizontally at a proper elevation above the ground whereon the warehouse is erected.

As before indicated, the improvement is specially adapted for use as a movable platform between a warehouse such as B, and a car C, that is located on a track parallel with and comparatively near to the side or end of the warehouse, the gang plank A being designed to bridge the gap between the floor of the warehouse and the floor of the car, extending from or through open doors, so as to provide a stable, temporary avenue for the transfer of freight between the car and house.

An aperture c of rectangular form is cut below the sill of the door opening B² in the warehouse B, this aperture extending horizontally between two of the joists d that support the floor B'. A pair of similar shafts e, e' are journaled by their end portions in the joists d parallel with and at a proper distance from each other, the shaft e being located near the doorway, as shown in Fig. 1. These shafts have rollers g secured upon them at points which will permit the strips a of the gang plank A to rest upon the rollers when said device is slid through the aperture c, the distance between the floor B' and rollers allowing the plank structure to be freely inserted and traverse said space, so as to locate it completely below the floor when this is desired, the strips a then having a support on the rollers of both of the shafts e, e', thus sustaining the gang plank in a horizontal position. The transverse boards b are stiffened near their longitudinal centers by the strip a' that is thereto secured on their lower sides, which strip extends from end to end of the gang plank.

At the transverse center and rear end of the gang plank an anti-friction roller h is journaled or otherwise supported to rotate, the periphery of which roller is adapted to have a rolling engagement with the lower sur-

face of the floor B' when the gang plank A is drawn outwardly, thereby obviating a frictional contact of the inner end of said structure with the floor while it is being outwardly projected.

It is an advantage to construct the gang plank of such a proportionate length that a considerable portion will remain within the cavity below the floor B' when there has been 10 an extension of the part A, effected to form a bridge between the warehouse floor B' and car floor C', and thus afford a counterbalance for the projected portion which aids in the manipulation of the gang plank to adjust it for 15 service.

When the improved gang plank A is drawn outwardly to connect its outer end with a car such as C, at its side door opening, if said car is furnished with a horizontal longitudinally 20 extending guide bar i, as usual, for the lateral support of the sliding door C² of the car, the hook plates m that are attached to the lower face of the gang plank near each side edge, are made to interlock their depending 25 lips with the guide bar, as represented in Fig. 3, and as said bar is placed a short distance below the floor C' of the car, it will be seen that the upper surface of the gang plank may lie nearly in the same plane with the floor C'. 30 The outer end portions of the side pieces a are preferably sloped on their upper sides, and thus adapted to receive the apron n, which is correspondingly sloped on the lower surface so that when in place on the pieces a, 35 the top of the apron named, will align with the upper surface of the gang plank, as shown in Figs. 3 and 4. The apron n is hinged upon the upper corner of the gang plank A by the adjacent transverse edge of its sloped face, so 40 that it may be imposed upon the inclined face of the gang plank as indicated by full lines in Fig. 4, or be outwardly folded as shown by dotted lines in said figure, thereby affording a continuation of the sloped top face of 45 the gang plank, so that when the latter is laid directly upon the floor C' of the car, there will be an inclined plane provided at this terminal of the gang plank which will facilitate the rolling of a loaded truck from the car to 50 the plank, and the reverse. The sloped faces of the strips a at the outer end of the gang plank A, are preferably covered by a secured metal plate n' of sufficient thickness to sustain any weight that may be transferred along 55 said gang plank, and the inclined face of the apron n is, in a like manner, protected by a similar plate n², as shown in Fig. 4.

It may occur that when the gang plank A has its outer end supported upon the guide 60 bar i of the car the relative position of said bar may be such as will dispose the upper surface of the gang plank above the floor of the car; in such a case, the flap plate o, which is hinged by one edge to the normally 65 upper edge of the apron n, will be of service to produce an inclined extension from the edge of the apron to the floor C', as shown in

Fig. 3. As the gang plank A, when drawn out for service, is located somewhat below the floor B' of the warehouse, there is an apron 70 p hinged by one of its side edges to the sill of the warehouse door opening B², so that it may hang pendent over the aperture c and be secured in such a position by a lock p' or other means, or the apron may be outwardly projected so as to form a slightly inclined extension from the door-sill, resting its outer end upon the gang plank, thereby affording a smooth track for a truck or the rolling of barrels 75 upon the gang plank and into the warehouse, or out of the latter to transfer such heavy articles into a car that the gang plank 80 A is in connection with.

It will be seen that by the provision of the improved gang plank, there is a substantial 85 temporary bridge afforded that will be adjustable for different heights of car floors, that may be extended more or less as occasion may require, and which, when not in use, can be safely housed out of the way and in a convenient manner for a quick adjustment for 90 renewed service.

It is evident that the gang plank A may be utilized for the transfer of goods from the ground to the elevated floor of the warehouse 95 when this is needed, or for a movement of heavy articles from the warehouse into a wagon or the reverse, if this be desired.

Having thus fully described my invention, I claim as new and desire to secure by Letters 100 Patent—

1. A gang plank, comprising a framed structure sloped on its top edges at one end, a wedge shaped apron hinged thereto, and a flap plate hinged to said apron and which may be outwardly folded to form a longitudinal extension for the apron, substantially as described. 105

2. A gang plank, comprising a framed structure, sloped at one end, a sloped apron hinged thereto and adapted to fold on the sloped face 110 and render the frame edges parallel at their sloped ends and also adapted to fold away from the end of the frame and provide an extension therefor, substantially as described.

3. A gang plank, comprising a framed structure, sloped on top at one end, a facing plate secured on said sloped surface, and a slope faced apron hinged to the sloped end of the frame structure, that when folded thereon affords a level top for the sloped edges of the 115 frame, and when extended provides a continuous longitudinally extended sloped surface therefor, substantially as described.

4. In a gang plank, the combination with a frame structure sloped on top at one end, and 120 hooks below thereon at said end, of a slope faced apron hinged by one edge to the sloped end of the frame and adapted to fold and render the frame level on top at said frame end, or be extended from the frame and afford a continued sloped face therefor, substantially as described. 125

5. In a gang plank, the combination with a rectangular framed structure sloped at one

end on its top face, of a slope faced apron hinged thereto at said end, a facing plate on the slope face of the frame, a facing plate on the sloped face of the apron, and hooks on 5 the frame end below said apron, substantially as described.

6. The combination with rollers on shafts journaled in timbers of a building below its floor, of a gang plank adapted to travel on 10 said rollers through an aperture in the build-

ing wall, and an apron hinged above the aperture to said wall and adapted to rest on the extended gang plank when said gang plank is extended and form a part of the top surface thereof, substantially as described.
